DISABLING AND INCAPACITATING GAS
GENERATING CHEMICALByron C. Goss, Cleveland, Ohio, assignor to
United States Ordnance Engineers, Inc., Cleve-
land, Ohio, a corporation of Ohio

Application March 1, 1932, Serial No. 596,103

6 Claims. (Cl. 167—47)

This invention relates to disabling and incapacitating gas generating chemicals, of the "tear gas" type, and to mixtures of such chemicals, which when "fired" produce disabling gases and disabling gaseous mixtures, or "suspensions" that cause excessive lachrymation accompanied by violent skin irritation, coughing, sneezing, and pain in the eyes, nose, throat and chest, and otherwise completely disable and incapacitate the persons subjected to the action of such gases and gaseous mixtures.

An object of the invention is to provide a composition of disabling and incapacitating gas generating chemicals which will produce a disabling and irritating gas or gaseous mixture, or "suspension", of the "tear gas" type, which is very effective in unusually low concentrations.

A further object is to provide a composition of disabling and incapacitating gas generating chemicals which will produce a gas or gaseous mixture or "suspension" that is exceedingly powerful in its disabling and irritating effects on the part of the person subjected to its action, in that said disabling gas or gaseous mixtures or "suspension" is far more severe in the punishment inflicted than known gases or gaseous mixtures in present use, and that is more difficult to exclude by gas masks than other gases or other gaseous mixtures of the type now in use.

30 A further object is to provide a composition of disabling and incapacitating gas generating chemicals which may be dispersed and volatilized and produce a disabling gas or gaseous mixture, or "suspension" by the use of cartridges, shells, bombs, grenades, and other disabling gas generating devices, etc., and that may be used in standard types of protection devices for safes, vaults, automatic and manually operated systems for protection against daylight hold-up attacks, 40 and also against night-time burglary attacks, for dispersing mobs, capturing criminals, etc., for use in fire arms and artillery, for spraying from airplanes, and other agencies for police and military use, and the like.

45 Other objects of the invention will be apparent to those skilled in the art upon reading the specification.

In the accompanying drawings,

50 Figs. 1 to 6 illustrate longitudinal sectional views of cartridges containing different types of charges of disabling gas generating chemicals and chemical compositions.

Fig. 7 is a longitudinal sectional view of a standard type of hand grenade charged with a 55 liquid disabling gas generating composition, and

also a charge of a gas under pressure, and also a central charge of high explosive.

Fig. 8 is similar to Fig. 7, except that it is charged with a disabling gas generating chemical composition in a powdered form.

Figs. 9 and 10 are plan and sectional views respectively of a type of spherical hand grenade charged with a liquid disabling gas generating chemical composition, and also a charge of gas under pressure, and also a charge of explosive; 10 and

Figs. 11, 12, and 13 are views, partly in section, of shells containing different types of charges of disabling gas generating chemical compositions, and also different locations.

The different types of cartridges, grenades, bombs, shells, etc., which are adapted for use with this invention, are referred to as "explosive devices".

In Fig. 1, a cartridge shell 1 is provided with 20 a primer 2, and a charge of explosive 3, and also a powdered disabling gas generating composition 4, the gas or gases generated carrying irritating and disabling "suspensions"; the cartridge may be "fired" with a pistol or other type of manual or automatic discharge device, and when "fired", the gas generating composition is volatilized and dispersed over a wide area. In Fig. 2, the cartridge shell 1 is provided with 25 a charge of powdered disabling gas generating composition 5, the gas or gases generated carrying irritating and disabling "suspensions", which composition is mixed with a suitable high explosive 6, and a large sized primer 7; the heat generated by the explosive increases the temperature of the mass of gas generating chemical 30 and volatilizes and distributes the same as mixed gas or gases and "suspensions" in a highly dispersed state, over a wide area. In Fig. 3, the cartridge 1 is provided with a charge of explosive 35 8, and a frangible capsule 9, for example, of gelatin, and a soft packing 10; the capsule 9 is filled with a liquid disabling gas generating chemical composition, and when the cartridge is "fired", the capsule is discharged and bursts and the liquid gas generating chemicals immediately 40 volatilize and produce a concentrated disabling gas atmosphere containing irritating and disabling "suspensions".

In Fig. 4, the cartridge 1 is filled with a mixture of powdered disabling gas generating chemicals 12, and a high explosive 13; a mass of high explosive 14 is also placed at the bottom of the cartridge next to the primer. This type of cartridge is adapted for a longer range service than 45 50 55

that illustrated in Fig. 2, the mixed explosive 12 generating considerable heat and volatilizing and distributing the disabling gas generating chemicals and irritating and disabling "suspensions" 5 over a wide area. In Fig. 5, the cartridge 1 is filled with a mixture of powdered disabling gas generating chemicals 15, and also a powdered dust-like solid, for example magnesium oxide 16, which latter is distributed as a cloud upon "firing" 10 the cartridge, the particles of magnesium oxide prevent caking of the charge, and facilitate scattering of the chemical, and also occlude or are saturated with the volatilized disabling gases and irritating and disabling "suspensions"; 15 the gases of which continue to evaporate therefrom for a considerable period of time and thereby keep the surrounding atmosphere "gassed" for a long period; a charge of explosive 17 is placed at the bottom of the cartridge. In Fig. 20 6, the cartridge 1 is charged with a liquid disabling gas generating chemical composition 18, and when "fired" the liquid is expelled and volatilized, distributing concentrated disabling gases and irritating and disabling "suspensions" over 25 a wide area, a charge of explosive 19 is placed at the bottom, below the disc 20.

In Fig. 7, a type of hand grenade 21, as disclosed in my application, Ser. No. 577,100, filed November 24, 1931, is provided with a nipple closure 22, to which is secured a tube 23; the grenade is charged with a liquid disabling gas generating chemical composition 27, and also with an excess of a gas under pressure 28, which gas is also dissolved to saturation in the liquid 27. The gas 30 28 35 may be a disabling gas, or it may be a neutral gas such as carbon dioxide, air, etc., or the substance 28 may be a low boiling liquid under pressure, for example, methyl chloride, ethyl chloride, etc., which is also dissolved to saturation in the liquid 27, and when the grenade is thrown and exploded the entire contents will be heated and volatilized, the compressed heated gas expanding and distributing the disabling gas and irritating and disabling "suspensions" over a much wider 40 area than would be the case if a compressed gas had not been added to the chemical charge in the grenade. The detachable bouchon 24 is provided with a powerful explosive 25, for example, "tetryl", mercury fulminate, E. C. blank fire powder etc., and a suitable match or fuse 26.

In Fig. 8, which otherwise resembles Fig. 7, the grenade is filled with powdered disabling gas generating chemicals 29 of suitable composition, for example, such as described above under Fig. 55 52; the grenade may also contain some gas under pressure, for example, a disabling gas, or a neutral gas, such as solid carbon dioxide, or a highly volatile liquid such as methyl chloride or ethyl chloride; when the grenade is exploded, the compressed gas will considerably aid in the distribution of the volatilized disabling gases and irritating and disabling "suspensions".

Figs. 9 and 10, illustrate an improved type of hand grenade 30, disclosed in my application, Serial Number 566,333, filed October 1, 1931, and is charged with a liquid disabling gas generating composition 31, and a compressed gas or highly volatile liquid in the space 32, as described under Fig. 7. This type of grenade is provided with a weight 33 on the end of the discharge tube 34, which discharge tube contains the match 35, match head 36, and a fusible closure 37; when the grenade is thrown, it "fires", bursting the closure 37, and upon landing on the ground, it 70 assumes the position shown in Fig. 10, the con-

tents of the grenade being blown from the mouth 38 of the tube 34 as a continuous high pressure stream of disabling gases, the force of the discharge of the gases twirling the grenade about, and also bouncing the same upon the land, and thereby more thoroughly distributing the disabling gases and irritating and disabling "suspensions."

In Fig. 11, a shell 40 as disclosed in my application, Serial Number 577,100, is provided with a detachable firing head 41, the shell contains a charge of high explosive 42, and also an additional charge of high explosives 43, for example, tetryl, etc., which violently bursts the shell upon firing; the explosive 43 is covered with metal foil 48. The shell 40 also contains a vessel 44 of glass, which contains a liquid disabling gas generating chemical composition 45, and also a charge of gas, or volatile liquid such as methyl chloride, under pressure, 46, which is also dissolved to saturation in the liquid 45, as described under Fig. 7. A body of gas generating chemical powder may also be placed at 47. When the shell is fired, the heat of the explosion bursts the shell and also the vessel 44, and volatilizes the gas generating chemical 45 which develops the mixed disabling gas and the irritating and disabling "suspension", and distributes the same with the aid of the compressed gas over an enormous area.

In Fig. 12, the shell 50 contains a centrally disposed tube 51, filled with a high explosive 52, such as tetryl, etc., and a detachable firing head 53. The shell 50 is charged with a liquid disabling gas generating chemical compound 54, and a compressed gas or volatile liquid 55, such as described under Fig. 7. In Fig. 13, the shell 60 otherwise resembles that shown in Fig. 12, but is charged with a powdered disabling gas generating chemical composition 64, for example such as described above under Fig. 8. When fired, the shell 60 is violently exploded and the gas generating chemical composition heated and volatilized and develops the mixed disabling gas and irritating and disabling "suspension" which mixture is distributed over a very wide area.

The disabling gas generating chemical composition contains as a principal ingredient, or may consist entirely of, vanillyl-normal-heptoylamide which when volatilized produces a highly irritating and disabling "suspension"; or this compound 50 may be substituted entirely or in part by any one or more of the following which also produce similar highly irritating and disabling "suspensions" when volatilized—

Vanillyl-normal-hexoylamide, vanillyl-normal-55 octoylamide, vanillyl-normal-nonylamide, vanillyl-normal-decoylamide, vanillyl-normal-undeocoylamide, vanillyl-normal-dodecoylamide all of which are solids, and may be used as such either alone or mixed with other solid disabling gas 60 generating chemical compounds, or they may be dissolved in disabling gas generating liquids, or in liquids which function as solvents for both said chemical and for the liquid gas generating chemical compounds; or several liquid disabling 65 gas generating chemical compounds may be mixed with each other, the resulting liquid also functioning as a solvent or suspension medium for the vanillyl-normal-heptoylamide or equivalent; also the vanillyl-normal-heptoylamide or equivalent may be suspended in a saturated solution of the same in a liquid gas generating chemical composition solvent. When liquid gas generating chemical compositions are used they may be placed in the cartridges, grenades, or shells illus- 70 75 75

trated in Figs. 3, 6, 7, 10, 11, and 12. Preferred liquid solvents, which are also gas generating compounds, are—

5 Ethyl-brom-acetate, methyl - brom - acetate, chloracetone, benzyl-bromide, brom-benzyl-cyanide, iodo-acetate, phenyl-iso-cyanide, bromo-acetone, chloro-methyl-chloroformate, chlor-acetol-
10 uone, phenyl-carbylamine-chloride, croton aldehyde, and chlorpicrin; there also may be used as simple solvents alcohol, ether, chloroform, and furfural; other liquids may also be used in addition to those above noted.

When used in the powdered state the vanillyl-normal-heptoylamide or equivalent may be used 15 alone or may be mixed with any one or more of the following disabling generating chemicals—

20 Chloracetophenone, phenyl-brom-acetate, di-phenylamine - chlorarsine, p - brom - chloracetophenone, iodo-acetophenone, diphenyl-chlorarsine; other disabling gas generating chemicals 25 may also be used; or the above powdered chemicals may be dissolved or suspended in disabling gas generating chemical liquids. A highly efficient disabling gas generating composition consists of about seven percent of vanillyl-normal-heptoylamide, or equivalent, and about twenty-five percent of chloracetophenone, both dissolved in about sixty-eight percent of ethyl bromacetate; this mixture produces extremely effective results 30 in that it combines the violent coughing and sneezing effect due to the vanillyl-normal-heptoylamide "suspension", with the lacrymatory nose and skin irritant effect of the solution of chloracetophenone in ethyl-brom-acetate, which latter is extremely effective as an irritant 35 of the nose and eye, in addition to its function as a solvent for the solids. As noted above, a mixture of solid disabling gas generating chemicals may be used, for example, diphenylamine-
40 chlorarsine may be added to or substituted for the chloracetophenone. Special mixtures or solutions of the above chemicals may be used for particular purposes, with wide variations in the percentage compositions.

45 Among highly efficient powdered mixtures of disabling gas generating chemicals, there may be used two percent of the vanillyl-normal-heptoylamide or equivalent, about six percent of diphenylamine - chlorarsine, about eighty - four percent of chloracetophenone, and about eight percent of magnesium oxide, all powdered and mixed, and passed through a 100 mesh screen. Or the vanillyl-normal-heptoylamide may be 50 mixed only with diphenylamine-chlorarsine, or with chloracetophenone, or other mixtures may be used according to the particular service desired. The vanillyl-normal heptoylamide or equivalent as described herein has been found to be highly efficient when dispersed as a "suspension", as an agent to produce violent coughing

5 and sneezing when in concentrations as low as 0.00005 milligrams per liter of air, whether used as a powder or as a dispersed liquid chemical composition in any of the illustrations herewith. The vanillyl-normal-heptoylamide, or equivalent, may be mixed in any proportion with any one or more of the solid disabling gas generating chemicals noted above, and if desired, said mixture may also contain finely powdered magnesium oxide which 10 serves to prevent caking of the mass in the explosive device, and which also effectively aids in scattering of the "suspensions" or vapors or gases of the volatilized disabling gas generating chemicals.

15 The group of disabling gas generating chemical compounds including vanillyl-normal-heptoylamide, vanillyl-normal-hexoylamide, vanillyl-normal-nonoylamide, vanillyl-normal-decoylamide, vanillyl - normal - undecoylamide, vanillyl-normal-dodecoylamide, is referred to in the 20 claims as the "vanillyl-normal-heptoylamide group".

I claim:—

1. A disabling gas generating chemical composition which generates irritating and disabling 25 "suspensions", containing vanillyl-normal-heptoylamide, associated with an auxiliary pressure generating agent.

2. A disabling gas generating chemical composition which generates irritating and disabling 30 "suspensions", containing vanillyl-normal-heptoylamide, associated with carbon dioxide under pressure.

3. A disabling gas generating chemical composition which generates irritating and disabling 35 "suspensions", containing vanillyl-normal-heptoylamide, associated with a charge of a high explosive, and an auxiliary pressure generating agent.

4. A disabling gas generating chemical composition which generates irritating and disabling 40 "suspensions", containing vanillyl-normal-heptoylamide, associated with chloracetophenone, and carbon dioxide under pressure.

45 5. An explosive device containing a charge comprising a disabling gas generating chemical composition which generates irritating and disabling "suspensions", containing vanillyl-normal-heptoylamide, another disabling gas generating chemical, a charge of high explosive, and an auxiliary pressure generating agent.

6. An explosive device containing a charge comprising a disabling gas generating chemical composition which generates irritating and disabling "suspensions", containing vanillyl-normal-heptoylamide, chloracetophenone, and a charge of a high explosive, said entire mass also associated with carbon dioxide under pressure.

BYRON C. GOSS. 60
